(57) **CLAIM**

The ornamental design for a lamp, as shown and described.

DESCRIPTION

FIG. 1 is a perspective view of a lamp showing the claimed new design;

FIG. 2 is a front elevational view thereof;

FIG. 3 is a left side elevational view thereof;

FIG. 4 is a top plan view thereof;

FIG. 5 is a bottom plan view thereof; and,

FIG. 6 is a detail view of area 6 in FIG. 5.

The broken lines immediately adjacent to the claimed portions are boundaries, all other broken lines are environmental structures; all the broken lines form no part of the claimed design.

1 Claim, 6 Drawing Sheets

FIG. 6

FIG. 1

FIG. 2

FIG. 3

FIG. 4

FIG. 6
